UNITED STATES PATENT OFFICE.

JOHN F. OLIVER, OF COUNCIL BLUFFS, IOWA.

DETACHABLE CELLAR-SPRAY.

No. 909,654.

Specification of Letters Patent.

Patented Jan. 12, 1909.

Application filed November 23, 1907. Serial No. 403,575.

To all whom it may concern:

Be it known that I, JOHN F. OLIVER, a citizen of the United States, residing at Council Bluffs, in the county of Pottawattamie 5 and State of Iowa, have invented certain new and useful Improvements in Detachable Cellar-Sprays, of which the following is a specification.

This invention relates to attachments for 10 the nozzles of fire hose, to provide means for discharging the water in the form of laterally projecting sprays, or finely divided particles of water, and has for its object to provide a simply constructed device of this 15 character which may be readily attached to an ordinary hose nozzle without change of structure of the latter or interference with its ordinary operation.

Another object of the invention is to provide 20 a simply constructed device of this character whereby the water discharged from the inner end of the device or the portion next to the hose nozzle will be projected in relatively large volume, or in a plurality 25 of relatively large jets directed rearwardly or toward the nozzle, while the water at the outer portion of the device is projected in outwardly and forwardly extended finely divided sprays or jets, while the water will 30 be projected at the central portion of the device substantially at right angles thereto and in relatively large jets, so that the water will be utilized to dispel the smoke in the neighborhood of the nozzle for the protection of 35 the operator, while the disseminated sprays at the outer end will operate effectually in subduing the fire.

With these and other objects in view, the invention consists in certain novel features 40 of construction, as hereafter shown and described and particularly pointed out in the claims, and in the drawing is shown the preferred form of embodiment of the invention, Figure 1 representing the improved device 45 in longitudinal section and applied to an ordinary hose nozzle, the latter being in plan view. Fig. 2 is an elevation of the body portion of the improved device detached. Fig. 3 is a detached perspective view of the mutilated threaded collar whereby the body portion is coupled to the nozzle, the portion of the device shown in Fig. 3 also illustrating a slight modification in the construction.

Fig. 4 is a view on a smaller scale illustrating the operation of the device.

55

It is frequently desirable in subduing fires that are inaccessible to the ordinary stream from the hose to project the water in the form of a spray or widely disseminated jets, especially where the fire is in close proximity 60 to a roof or beneath a floor or a similar location, and in operating devices of this character, an aperture is made in the floor or roof, and the spraying implement inserted, and the water discharged as before described in 65 the form of widely disseminated sprays or jets, and the improved device herein shown is designed to be employed in connection with the discharge end of an ordinary hose as used by firemen, and consists in a hollow 70 body portion 10, preferably in globular form and with an intake 11 at one side corresponding to the discharge of a hose nozzle, and with an enlarged internally threaded socket 12, the latter adapted to bear over the 75 outer beaded end or top 13 of an ordinary hose nozzle 14, the socket being considerably larger than the bead of the top, as shown in Fig. 1.

Adapted to be passed over the neck portion 80 of the nozzle 14 is a securing element consisting of a substantially U-shaped collar 15 externally threaded to engage the threads of the socket 12, when passed over the nozzle and rotated. A packing 16 of rubber, 85 leather, or similar material is inserted between the socket 12 and the top portion 13, as shown.

The member 15 is provided with projections 17 to receive a spanner wrench or like 90 implement to enable the threaded member to be rotated to cause it to enter the socket, as will be obvious. By this simple means when the improved device is required, the fireman simply slips the socket portion 12 95 over the end of the nozzle, and then passes the member 15 over the neck portion of the nozzle below the socket 12 and rotates it to cause the teeth to engage the teeth of the socket, until the inner end of the member 100 15 bears against the inner edge of the bead 13, and thus firmly lock the body portion 10 to the nozzle. This action may be accomplished very quickly, and does not require the fireman to disconnect any parts of the 105 nozzle, or make other changes in the struc-

ture, and when the spray device is no longer required it can be as readily detached by simply loosening the member 15 and removing it from the socket.

5 The body 10 is provided with three novel forms of jet or spray apertures, as shown.

The outer portion of the body is provided with a plurality of radially disposed relatively fine apertures 18, the central portion 10 of the body provided with relatively coarse or large elongated apertures 19 disposed substantially at right angles to the longitudinal plane of the nozzle, and a plurality of elongated apertures 20 each disposed at 15 an angle to the longitudinal plane of the nozzle, or the longitudinal plane of the improved attachment. By this means when the water is turned on by manipulating the cut-off element illustrated at 21 in Fig. 1,

20 it will be projected through the relatively large apertures 20 backwardly toward the nozzle, and by the inclined form of apertures 20 will be caused to assume a circular shield of water between the fireman and the 25 fire or the origin of the smoke, and effectually eliminate the smoke and protect the fireman, while the water projected through the relatively large apertures 19 will form a second circular wall of water which will effectually

30 drown out any fire immediately in the vicinity of the nozzle, while the finely divided sprays or jets passing through the apertures 18 will produce the usual effect of the spraying action. By this simple arrangement a 35 very effective device is produced, which may be simply constructed, inexpensively manufactured, and readily applied to a hose nozzle without alteration therein or the removal of any of its parts.

40 The device may be quickly applied and as quickly removed, as above described. The device may be constructed of any required material, and of any size to adapt it to variations in the forms and sizes of hose nozzles, 45 and of any required material, but will preferably be of the same material as the nozzle, which is usually of brass or similar compounds. The mutilated collar 15 is formed large enough so that it will readily pass 50 over the neck portion of the hose, as illustrated in Fig. 1.

Having thus described the invention, what is claimed as new is:—

1. A spray head comprising a hollow body 55 having a plurality of jet apertures and also having an annular socket at one side adapted to embrace the discharge end of the nozzle and through which communication is provided between the nozzle and the hollow 60 body, and a substantially U-shaped member to fit between the nozzle and hollow body for interlocking the hollow body and nozzle together.

2. A spray head comprising a hollow body 65 having a plurality of jet apertures and with

an annular socket at one side adapted to engage the discharge end of the nozzle and through which communication is provided between the nozzle and the hollow body, and a mutilated collar engaging the socket and 70 adapted to bear over the nozzle and against the projecting portion of the tip thereof.

3. A spray head comprising a hollow body having means for detachable connection to a hose nozzle and provided with a plurality of 75 relatively small spray apertures in its outer part, a plurality of relatively large elongated apertures near its juncture with the nozzle and each arranged at an angle to the longitudinal plane of the nozzle, and a plurality of relatively large elongated apertures 80 intermediate the before mentioned apertures and each disposed at right angles to the longitudinal plane of the nozzle.

4. A spray head comprising a hollow body 85 having an annular socket adapted to pass over the discharge end of the nozzle and internally threaded, an exteriorly threaded mutilated collar adapted to bear over a nozzle and engage the threaded socket and bear 90 against the under side of the top enlargement of the nozzle.

5. A spray head comprising a hollow body having an annular socket adapted to bear over the discharge end of the nozzle and internally threaded, a threaded collar adapted 95 to engage the threaded socket and bear against the tip enlargement of the nozzle, said body having a plurality of relatively small spray apertures in its outer part, a plurality of relatively large elongated apertures near the socket and each arranged at an angle to the longitudinal plane of the nozzle, and a plurality of relatively large elongated apertures intermediate the before mentioned 100 apertures and each disposed at right angles to the longitudinal plane of the nozzle.

6. A spray head comprising a hollow body including a perforated globular portion and an intake whose free end is enlarged exteriorly and interiorly, the enlarged portion being adapted to embrace the outer end of the nozzle, and a substantially U-shaped member arranged to fit between the nozzle and said head to lock the head and nozzle 110 together.

7. A spray head comprising a hollow body including a perforated globular portion and an intake portion whose free end is enlarged exteriorly and interiorly, the enlarged portion being adapted to embrace the outer end of the nozzle, and a substantially U-shaped member arranged to fit between the nozzle and said head to lock the head and nozzle 120 together, said member having projections 125 whereby it may be worked into and out of operative relation with the nozzle and head.

8. A spray head comprising a hollow body including a perforated portion and an intake portion, the latter being formed for co- 130

operative engagement with the nozzle, and a substantially U-shaped member for engagement between the nozzle and head to detachably lock the head and nozzle together.

5 9. A spray head comprising a body including a hollow portion and an intake portion, the hollow portion being globular in form and having the outer part of its globular portion perforated, with its inner part provided with elongated apertures and each arranged at an angle to the longitudinal plane of the nozzle and also having a plurality of elongated apertures intermediate the before mentioned apertures and each disposed at a 10 right angle to the longitudinal plane of the nozzle, and means for locking the nozzle and head together.

10 10. A spray head comprising a body including a hollow portion and an intake portion, the hollow portion being globular in form and having the outer part of its globular portion perforated, with its inner part provided with elongated apertures and each arranged at an angle to the longitudinal plane of the nozzle and also having a plurality of elongated apertures intermediate the before mentioned apertures and each disposed at a 15 right angle to the longitudinal plane of the nozzle, and means for locking the nozzle and head together.

15 11. A spray head comprising a body including a hollow portion and an intake portion, the hollow portion being globular in form and having the outer part of its globular portion perforated, with its inner part provided with elongated apertures and each arranged at an angle to the longitudinal plane of the nozzle and also having a plurality of elongated apertures intermediate the before mentioned apertures and each disposed at a 20 right angle to the longitudinal plane of the nozzle.

20 rality of elongated apertures intermediate the before mentioned apertures and each disposed at a right angle to the longitudinal plane of the nozzle, and a U-shaped member adapted to fit between the intake portion of the head and the nozzle to detachably connect the head and nozzle together.

25 11. A spray head comprising a body including a hollow portion and an intake portion, the hollow portion being globular in form and having the outer part of its globular portion perforated, with its inner part provided with elongated apertures and each arranged at an angle to the longitudinal plane of the nozzle and also having a plurality of elongated apertures intermediate the before mentioned apertures and each disposed at a 30 right angle to the longitudinal plane of the nozzle.

30 In testimony whereof I affix my signature, 35 in presence of two witnesses.

JOHN F. OLIVER.
